SANDING DEVICE

Patrick Farrell, Irvington, N. J.

Application November 3, 1938, Serial No. 238,519

4 Claims. (Cl. 291—38)

This invention relates to an improved sanding device to be used on self-propelled vehicles and particularly on automobiles.

The invention is designed to provide a device which includes a receptacle for sand or the like and which is provided with an outlet pipe to deliver the sand in front of a wheel of the vehicle and a valve for controlling the flow of the sand.

10 The object of the invention is to provide a receptacle for the sand which receptacle can be manipulated to free or loosen sand that has become caked or hard and thus avoid the necessity of securing a stick or other device for insertion 15 into the bag which latter has heretofore been necessary. Another feature of the invention is a flexible feed pipe for conducting sand from the receptacle, the feed pipe being flexible to provide a means for dislodging any sand that 20 might remain in it and for easy installation in cars of different makes and sizes with a possible difference in the proportion of the parts on which the device is mounted.

25 The invention is illustrated in the accompanying drawing in which Figure 1 is a side view of the invention and showing part of an automobile in dotted outline. Figure 2 is an enlarged detail view of the device with the feed tube or pipe broken off. Figure 3 is an enlarged section of the valve used in the device. Figure 4 is a section on line 4—4 in Figure 3. Figure 5 is a perspective view showing one way of connecting the valves of two devices when used for both wheels of a vehicle.

30 To illustrate the most common use of the device, I show it on an automobile and arranged to deposit sand, when needed, in front of the rear wheels of the automobile. The device comprises a receptacle 10, a valve 11, a feed pipe 12 and means for operating the valve 11, in this illustration the means consisting of a rod 13 and pivoted lever 14. The operation of the device is accomplished by opening the valve 11 and allowing sand or the like to flow down through the pipe 12 and be deposited in front of the wheel 15 of the automobile. This occasional use of the device is necessary at times when the roadway is covered with ice or other slippery coating and also in muddy or soft ground. The invention is resident in details which contribute to a more efficient and reliable delivery of sand.

35 The receptacle is flexible, the valve is constructed to readily release the sand and the flexible tube is adapted for temporary flexing if

the sand is to be deposited directly under the wheel.

The receptacle 10 is usually made of a canvas although other loose material or fabric can be used. The bag is suspended by suitable means 5 and it is preferable to have it readily removable both from the suspending means and the valve. I show the bag or receptacle suspended from hooks 16 and placed in the rear compartment of the automobile. This is the usual place where 10 the bag is installed but it will be apparent that it can be arranged in any conveniently accessible place provided the outlet channels are arranged to allow a substantially vertical flow of the sand. A flexible bag is of advantage for the reason 15 that prior to use the bag can be squeezed and manipulated to loosen the sand inside and make certain that it is not caked. This makes it unnecessary to procure a stick or other tool and poke it into the sand which is the case in fixed 20 or rigid receptacles like boxes. The base or outlet of the bag can also be pushed in and manipulated to distort the sand in the outlet to the valve 11. The flexible bag is sharply tapered or usually circular in cross section. The 25 bag is greater in height than in width, and being suspended it facilitates the downward flow of escaping sand and lends itself readily to the squeezing or tapping that enables the operator to quickly and easily dislodge any caked sand 30 contents of the bag.

The valve 11 is fixed in place, usually on the floor or shelf of the rear compartment and comprises a plate 17 with a flange 18 on the top. The bag is detachably secured to the flange 18 35 by any suitable means but preferably by a ring 19 secured to the bag and fitting over the flange and with a bayonet lock 20 or other means for fastening the ring and flange together. This connection is also of utility by allowing a partial opening of the lock and a shaking of the bottom of the bag without removing it completely from the valve. The inside of the flange on one side is inclined as shown at 21.

The valve has a movable valve member in the 45 form of a slide 22, yieldingly held in place by the spring or springs 23 secured to the slide and to the plate 17. The slide is connected to the rod 13 by means of which it is positively operated. The inner end of the slide, when the valve is 50 shut, abuts on the bottom of the inclined bottom or side 21 of the flange 18 and thus serves to close the passage 23 through the valve. On the bottom of the valve is a flange 24 to which is attached the outlet tube or pipe 12. The out- 55

let pipe is secured in any suitable manner. I show a bolt 25 as one means of securing the outlet pipe in place.

The outlet tube passes from the valve 11 which is inside the case to the outside of the car through a hole made in the body of the car under the mud guard and then hangs down in front of the wheel 15. The pipe is of the metallic flexible type which can be forcibly bent but remains in its position under normal strains. This allows for its ready installation in an automobile and to be bent into place in various makes of cars in which the dimensions vary slightly. Another advantage is that in some instances it is necessary to feed sand directly under the wheel and in this instance the pipe can be bent with its outlet directed under the tire.

The normal position however is in front of the wheel where the wheel rests on the ground and thus feed sand while the car is in motion. This is particularly advantageous in the initial phase of skidding or in moving over ice or slippery places, especially on inclines.

In the usual installation two complete units are provided, one on each side, but they are operated simultaneously. I show a cross rod 26 in Figure 5 which cross rod operates a second rod 27, which is connected to a second valve and operates simultaneously with the rod 13.

30 I claim:

1. A sanding device for vehicles comprising a bag, a pipe for conducting sand from the bag

and a valve at the bottom of the bag and closely adjacent thereto, the bag being made of flexible fabric, and means for suspending the bag above the valve whereby the bag can be manually distorted to free any caked contents adjacent the 5 valve.

2. A sanding device for vehicles comprising a freely flexible bag, a pipe for conducting sand from the bag, and a valve at the bottom of the bag and closely adjacent thereto, the bag being 10 sharply tapered and made of flexible fabric, and means for suspending the bag above the valve whereby the bag can be manually distorted to free any caked contents adjacent the valve, the bag including a connection to the valve which 15 connection is readily detachable.

3. A sanding device for vehicles comprising a vertically disposed flexible bag made of readily flexible fabric, a valve for conducting sand from the bottom of the bag, means for suspending the 20 bag to allow the bag to be manipulated for the freeing of caked material in the bag, and a metallic flexible non-collapsible tube secured to the valve for conducting material to the location desired. 25

4. A sanding device for vehicles comprising a readily flexible bag of fabric, means for suspending the bag from a portion of a vehicle to allow the bag to be manipulated for freeing caked material in the bag, an outlet pipe, and a valve 30 between the outlet of the bag and the pipe.

PATRICK FARRELL.
